CONVEYER APPARATUS

Robert J. Stewart, Baltimore, Md., assignor to
Crown Cork & Seal Company, Inc., Baltimore,
Md., a corporation of New York

Application September 9, 1941, Serial No. 410,223

5 Claims. (Cl. 198—22)

The present invention relates to a conveyer driving mechanism and, more particularly, to a conveyer drive for the infeed portion of a filling machine.

Containers to be filled are usually delivered to a filling machine by a continuously moving straight line conveyer moving from the bottle washer and which conveyer carries the containers toward a rotary infeed dial on the filler. When a container is directly adjacent the infeed dial, the movement of the conveyer will carry it into the dial pocket which next sweeps across the conveyer. The path of the container is generally along a straight line until it is in a dial pocket, and it then moves along a curved path. The conveyer and dial have heretofore been driven from the same source at fixed speed ratios.

It is highly important that filling machines shall not mar or damage containers handled thereby, and the area adjacent that at which the above mentioned transfer occurs is one at which containers are most apt to be damaged. More particularly, in sweeping across the conveyer, the infeed dial may rather forcibly engage a container if the latter is not moving at a speed closely approximating the dial speed or is not at the proper point for engagement by the dial, and the container may be sharply moved against the guide elements which cooperate with the conveyer and dial. Also, under such circumstances, the container may even become momentarily jammed between the dial and the guide elements.

Another cause of containers, and particularly bottles, becoming marred is due to the fact that bottling plants usually have the bottle washing machine produce washed bottles at a slightly higher rate than the filling machine can receive them. The purpose of this practice is to insure that each filling head of the filling machine will receive a bottle, and the surplus rate of supply permits this to occur even though some washed bottles may be removed from the straight line conveyer by an inspector before they reach the filling machine. This common system of operation also allows for a temporary stoppage of the washing machine. In any event, the practice results in the presence of a line of contacting bottles on the straight line conveyer.

Containers which do not require washing, such as cans, are also placed upon the conveyer in such manner and quantities that the above situation can occur.

In order that containers may be delivered to

the infeed dial in properly spaced arrangement to be synchronized therewith, it has been the usual practice to provide a gate or timing device on the conveyer and adjacent the dial. These timing devices have been controlled from the infeed dial in such manner that the containers would be released for movement to the dial in properly spaced order. The distance of the gate device from the dial has usually been varied according to the size of the containers being handled.

Nevertheless, the use of such gate device has contributed to the marring of containers due to the fact that when the leading container is released by the gate, the following contacting containers move sharply forward with the conveyer, and their movement is then suddenly stopped by the gate, causing the line of containers to be sharply jarred. Since the force of any such impact increases as the square of the container velocity, this cause of impact is increasingly important in connection with the trend toward fillers of higher output which require more rapid movement of all the container handling devices, including the infeed conveyer.

Generally speaking, the above difficulties are due to the fact that containers move at random upon the straight line conveyer and, during the latter portion of their movement thereon, are in contact so that their axes are spaced apart a distance equal to their overall diameters. However, the infeed dial is designed to handle them in a more widely spaced arrangement, which spacing is determined by the spacing between the filling nozzles and capping heads. Use of a timing device has heretofore been customary to obtain such spacing, but had the stated objection of jarring the containers.

Another point to be noted in connection with filling machines is the following: In order to enable a filler to handle containers of different sizes, a purchaser is provided with a different infeed dial for each size, each dial having a different outside diameter and pockets of slightly different conformation. It is also to be noted that the dials for each size container are so designed that the vertical axes of all containers, regardless of size, will move along the same curved path. That is, the infeed dials for all size containers have the same pitch circle. It is necessary to keep this pitch circle fixed because the vertical axes of the vertically reciprocable nozzles and capping heads of the filling machine are positioned on the pitch circles of their rotary carriers. Obviously, if the pitch circle of the in-

feed dial were changed for different sizes of containers, it would be extremely difficult to subsequently place the containers on the necessarily fixed pitch circles on which the nozzles and capping heads reciprocate. Therefore, an infeed dial intended for large containers will have deeper pockets than a dial intended for small containers and the guide elements surrounding the respective dials will be so positioned for each size container that they will guide all containers along exactly the same curved line.

Also, as has been generally stated above, because the circumferential spacing of the nozzles and capping heads is fixed, the axes of all containers must be kept apart fixed distances by the various sized infeed dials.

In any event, and even with the above changes for containers of different sizes, and also with the use of a timing device adjustable for size, it is frequently found that a machine will damage containers of one size to a much greater extent than it damages containers of another size. In other words, even though machines have heretofore been designed which would operate very smoothly and quietly with a container of one size, the same machine would be quite noisy when handling containers of another size and would badly mar such containers.

An important object of the present invention is to provide an arrangement for smoothly transferring articles from a conveyer on which they move at random to a conveyer adapted to handle them in spaced relation.

A further object of the invention is to provide a mechanism of the above type which does not require use of a timing device.

Another object of the invention is to provide a mechanism of the above construction which will satisfactorily and smoothly handle articles of various sizes.

I have found that the difficulties heretofore encountered with some sizes of containers upon a machine which satisfactorily handles another size can be corrected if the conveyer drive is so designed that containers are moved at a speed determined by their size. I have further found that if such a drive is provided, the usual timing device can be eliminated.

By the present invention, the conveyer and the rotary dial or other infeed element, instead of always moving at the same relative speeds, as has heretofore been the case, are connected by a variable speed connection, so that with each size or type of container, the two elements can be driven at a speed to cause containers to be properly synchronized or "meshed" with the dial pockets. That is, the conveyer may be driven faster with respect to the dial when larger containers are handled and the speed of the conveyer with respect to the dial can be reduced with smaller containers. The arrangement permits a speed relationship variable with each size container and enables all sizes to be synchronized with the dial.

While the present invention has been discussed above in connection with filling machines, it will be obvious that it is readily applicable to other apparatus for handling articles.

As has been stated above, containers crowd together on the conveyer adjacent the usual timing device. This means that a container is momentarily stopped at this point or its advancing movement at least reduced to a speed slower than the movement of the conveyer. Obviously, if the conveyer is moving at a linear speed corresponding to that of the dial, the stopped or retarded con-

tainer will not be accelerated by the conveyer to reach the dial pocket at the proper instant, and some jarring will occur at the moment of impact with the dial.

It has heretofore been proposed to correct the difficulty referred to in the preceding paragraph by interposing between a conveyer and a dial a more rapidly moving element to accelerate the movement of retarded or stopped containers to synchronize them with the dial. However, such arrangements are not applicable to correct the more important and more frequent difficulties arising from filling containers of different sizes and, in addition, require the provision of a third moving element which, with its guide elements, must usually be so arranged as to interfere with the established and most desirable path for the containers.

It has also previously been proposed to vary the spacing of articles on a receiving conveyer element by driving such conveyer at various speeds with respect to the delivery conveyer. However, it will be observed that the variation of the speed of the conveyer and dial of the present invention is not used to vary spacing, since all dials used on a given machine have the same number of pockets. Therefore, the present invention must overcome factors not contemplated by conveyer assemblies intended to vary the spacing of articles.

Other objects and advantages of the invention will be apparent from the following specification and accompanying drawings, wherein:

Figure 1 is a diagrammatic showing of a portion of a bottling plant and including the conveyer drive of the present invention.

Figure 2 is a fragmentary view showing the infeed portion of a filling machine in top plan, and

Figure 3 is a diagrammatic view, in plan, showing the manner of transferring containers of different sizes from a straight line conveyer to the rotary infeed dial of a filling machine.

Figure 1 shows a portion of a bottling plant layout and the numeral 10 designates a bottle washing machine from which containers are moved by continuously moving straight line conveyer 11. As is the usual practice, the washing machine 10 and straight line conveyer operate at such relative speeds that the washing machine bottle carrying conveyer 12, moving in the direction of the two parallel arrows, and including the usual diagrammatically shown rows 12a of bottle holding elements, will place a line of bottles upon the conveyer 11, the latter will move them to the right in Figure 1, and very shortly after the last container of the line has moved to the right of the bottle handling conveyer 12, the latter will deposit another line of bottles upon conveyer 11.

Conveyer 11 conducts the bottles to a transfer device 13 by means of which the bottles are diverted to a straight line conveyer 14 forming part of the filling machine 15. Straight line conveyer 14 conducts the containers to the rotary infeed dial 16 of the filling machine, which dial is removably keyed to its driving shaft 16a and is provided with spaced pockets. If the machine is a beer or milk filler, dial 16 moves the bottles directly to a filling table such as 17, while if the machine is a soft drink filler, dial 16 will conduct the bottles to a syruping mechanism 18 from which they are subsequently transferred to the filling table by an infeed transfer dial 17a. In either event, the bottles are removed from the

filling table by an outfeed transfer dial 17b which moves them to a rotary crowner or capper dial 19 from which they move through an outfeed dial 20 which again places the containers upon either the straight line conveyer 14 or a separate outfeed conveyer. A transfer device 21 may be provided to place the containers upon a conveyer 22 which conducts them to a further point in the bottling plant, for example, a beverage mixer, a labeler, or to a point at which they are placed in cases.

By the prior practice, a timing or gate device has been provided alongside conveyer 14 immediately in advance of dial 16.

As is usual, the filling table 17 carries bottle supports 17' having filling nozzles vertically aligned therewith and positioned on a circle which is the pitch circle of table 17 in that it registers with the pitch circles of the infeed transfer dial 17a and the outfeed transfer dial 17b. The syruping heads are positioned on the pitch circle of dial 18, if such heads and dial are provided, and crowning heads are positioned on the pitch circle of crowner dial 19.

Straight line conveyer 14 is driven from a shaft diagrammatically indicated at 23 and which is in turn driven from the variable speed driving mechanism generally indicated at 24 in Figure 1. The variable speed drive mechanism is of such type that the straight line conveyer 14 may be moved at any desired speed with respect to the various rotary container handling elements of the filling machine. More particularly, the usual drive motor for the filling machine may be provided, but instead of driving the straight line conveyer 14 directly from this drive, and always at the same linear speed ratio with respect to the rotary elements of the filling machine, the variable speed mechanism 24 is interposed in the driving mechanism of the machine for the purpose of driving the straight line conveyer shaft 23. By this arrangement, the straight line conveyer 14 can be driven at various speeds with respect to the rotary elements of the filling machine simply by adjustment of the variable speed mechanism. Alternatively, the rotary container handling elements of the filling machine can be driven by one source of power and the straight line conveyer 14 may be driven from a separate source of power so that the speed of movement of the straight line conveyer can be adjusted independently of the speed of movement of the rotary container handling elements including infeed dial shaft 16'.

It will be understood that in some instances the straight line conveyer 14 may extend entirely to the washing machine 10 and may also extend to the apparatus which receives the containers from the filling machine, thereby eliminating use of one or both of the transfer devices 13 and 21 and conveyers 11 and 22.

By the arrangement shown in Figure 1 the conveyer 11 is driven at the same speed as straight line conveyer 14 through the shaft 26. The outfeed conveyer 22 may also be driven at the same speed or it may be driven from a separate source of power.

Referring to Figure 2, guides 30 are provided alongside the straight line conveyer 14 to cause containers to be properly aligned upon the latter, and an arcuate guiding element generally designated by the numeral 31 extends about the path of movement of the rotary dial 16 to maintain containers in the dial pockets. The guide 31 may include a jam detector 32 which is adapted to

move outwardly in well known manner should a container come between it and the prong or tooth of the infeed dial, such outward movement of the detector causing the machine to be stopped.

5 In the disclosed arrangement, the detector 32 or the other corresponding portion of the guide 31 includes a shoulder 33 which serves to give each container a movement radially of the dial so as to move toward the dial pocket. The opposite portion of the guide 30 is correspondingly concaved as indicated at 34. Beyond shoulder 33 the guide 31 conforms to the path of movement of containers with the infeed dial 16.

The containers B illustrated at positions a to e in Figure 2 indicate how containers accumulate adjacent the infeed dial if no timer is used and due to the fact, hereinbefore discussed, that it is the practice to place containers upon or deliver them to conveyer 14 at a rate in excess of 15 the rate at which dial 16 can remove them. Because the containers at b and c are in contact and hence are more closely spaced than the capacity of dial 16, the movement of the container at position c is retarded below the speed of conveyer 14. The same is true of the container at position d and the conveyer 14 may therefore be moving faster than both of these containers.

20 If the conveyer 14 is always driven at the same linear speed with respect to the dial 16, regardless of the size of the containers, as was the prior practice, the speed of the container at position b would be a variable, depending upon whether it was markedly retarded with respect to the conveyer 14 before it was first engaged by the dial. 25 If it was so retarded, it may be moving too slowly for smooth and non-jarring engagement by the dial. If it is jarred by the dial, such a jar may be transmitted backwardly to the respectively contacting containers at positions c and d so that

30 they, as well as the container at b, will be marred.

Other factors affecting the movement of a container initially engaging the dial, as is the case with the container at position b, are hereinafter discussed in connection with Figure 3. The container at position e is moving entirely under control of conveyer 14 and the container at position a is moving entirely under control of dial 16.

35 It will be noted that if the containers at positions c and d in Figure 2 were held back by a timing device, they would be stopped, and the conveyer would move beneath them.

40 Figure 3 diagrammatically illustrates in more detail than Figure 2 the manner in which containers move from the straight line conveyer 14 to the infeed dial 16 by the present invention. Referring to this figure, a large container L is shown at position L2 in which position it is fully engaged by the pocket of the dial 16a fitted upon the shaft 16' to handle containers of this size. At such time, the guides 30 of the straight line conveyer 14 are spaced apart as shown in solid lines in Figure 3 and the guide 31 surrounding the infeed dial is positioned as shown in solid lines so as to be sufficiently spaced from the axis of the dial that containers of the size L can be accommodated within the dial pockets and their axes will move on pitch line P.

45 The container at position L2 has just been fully engaged by the infeed dial and has therefore just come fully under the driving force of the dial to pass entirely out of driving control of straight line conveyer 14. Also, at this moment, the succeeding container at position L1 is being maintained in contact with the container at position

LL2 under the action of the straight line conveyer. It will be understood that the two containers referred to may have been spaced apart at the time they were originally placed upon the conveyer system but the container at L1 approached the container now at L2 to come into contact with the latter as the two moved adjacent the infeed dial, due to the fact that a surplus of containers was placed on conveyer 14 to cause an adequate supply of containers to accumulate at the infeed of the filling machine.

It will be apparent from Figure 3 that before the container at position L1 can reach position L2, its axis must move from the point L3 to point L4.

Figure 3 also shows in dot and dash lines the arrangement of the various guide elements and the form of the infeed dial 16b when smaller containers S, also shown in dot and dash lines, are to be handled upon the machine. It will be observed that the dial 16b is of sufficiently large diameter and the guides are positioned sufficiently closely to the dial axis that the axes of the containers S will follow the same arcuate path P as the axes of the larger containers L. This path, the pitch circle of the infeed dial, must be maintained because it registers with the pitch circles of the filling table and crowning mechanism and these latter respectively carry nozzles and capping heads positioned to reciprocate on vertical lines intersecting the pitch circles of filling table and crowning mechanism, respectively. In other words, if a container were caused to move about the infeed dial on a path of different radius, i. e., a different pitch circle, some means would have to be provided to subsequently place the axis of that container on the pitch circle of the filling table so that the container would be kept aligned with the vertically moving filling heads.

The small container at position S2 has just come entirely under the driving force of the infeed dial 16b so that it now moves independently of the straight line conveyer 14. At position S1 there is indicated the next succeeding small container which is in contact with the container at position S2 due to the driving effort of the straight line conveyer 14, though conveyer 14 may now be moving somewhat faster than the container at position S1. The axis of the container at position S2 is indicated at S4 while the axis of the container at position S1 is indicated at S3.

It will be noted from Figure 3 that the large container L at position L1 must move a substantial distance before it reaches position L2, as compared to the distance which must be travelled by the small container S at position S1 to reach position S2. In other words, if the straight line conveyer 14 is always moving at the same speed relative to the infeed dial of Figure 3, and with the speed so set that the large container L at position L1 would reach position L2 in perfect synchronism with the infeed dial, a small container at position S1 would reach position S2 well ahead of the proper moment. For this reason, it is highly desirable to adjust the speed of the straight line conveyer 14 and the infeed dial 16a with respect to each other when different sizes of containers are being handled.

In accordance with the above, the variable speed mechanism 24 of Figure 1 would be adjusted by an operator so that the straight line conveyer 14 would move somewhat slower with respect to infeed dial 16b when small containers are being handled by the machine. When larger

containers are being handled, the variable speed mechanism 24 would be adjusted so that the straight line conveyer 14 would move more rapidly with respect to infeed dial 16a, thereby enabling a container to move from position L1 to position L2 exactly in synchronism with the dial.

It will be observed that, for practical purposes, point L4 is the point at which the axis of a large container L first reaches the pitch circle P. Similarly, the point S4 is that at which the axis of a small container S will first reach the pitch circle P.

Points S4 and L4 in Figure 3 show how the point at which containers are fully engaged by the dial is varied circumferentially of the dial path, according to the size of the container. This is customary to obtain smooth transfer.

The container at position L1 with its axis at point L3 is diagrammatically indicated as in the closest position to the pitch circle P which a container can occupy at the moment that the preceding container has just been fully engaged by the infeed dial. It will be observed that the distance that the axis of a container must move between these two points substantially corresponds to the diameter of the container because of the fact that the containers are in contact and their axes are thereby only separated by the radius of each container. Therefore, as stated above, it follows that a large container must move a greater distance from what is, in effect, its critical position with respect to the dial and conveyer movement, to the position when it will be fully under control of the dial.

The positions S1 and L1 are critical positions in connection with the movement of the containers to the dial in that in such positions the movement of the container is retarded because of its immediate contact with the preceding container and also because the preceding container is moving somewhat at an angle to the path of the containers at positions S1 and L1. In setting the speed at which the conveyer and dial are to move with respect to each other, this speed can be so adjusted that account will be taken of the fact that the containers at positions S1 and L1 are retarded and that the conveyer must perhaps accelerate their movement in order to place them in timed relation for synchronism with the dial pockets.

In construction of a machine of the type under discussion, index marks can be placed upon the adjusting mechanism of the variable speed drive mechanism 24 so as to indicate the ratio at which it should be set with containers of standard sizes. With this arrangement, the operator in a bottling plant would simply have to set the mechanism accordingly.

It has been pointed out above that instead of providing a variable speed drive mechanism 24 to enable the conveyer 14 to be driven at a speed different from that of the shaft carrying dial 16 and the remaining elements of the filling machine, the conveyer may be driven from an entirely different source of power, the speed of which can be adjusted with respect to the speed of the filling machine so that containers will reach the infeed dial 16 in synchronism.

While the invention is preferably used without a timing device, it will be noted that it may be followed with use of such a device by controlling the relative speed of conveyer 14 with respect to dial 16 according to the diameter of the container being handled. For example, a large container held by a timing device positioned at a given

point would have its axis spaced a further distance from position L2 in Figure 3 than would be the case with a small container. By adjusting the relative speeds of conveyer 14 and dial 16, allowance can be made for this factor.

It will also be understood that the invention is applicable to apparatus other than filling machines, in fact, it may be used with various types of article handling machines to enable articles to be delivered to a moving element in synchronism with that element and regardless of whether the articles have previously been moving at random. Dial 16 illustrated herein is adapted to be replaced with dials of different size and having pockets of different conformation. However, if desired a dial of well known type provided with mechanically adjustable pockets may be used. Alternatively, the size of the dial pockets can be reduced by superimposing thereon plates having smaller pockets, as is well known.

It will be clear from the above that the invention is of particular importance in connection with apparatus intended for use with articles having a large range of sizes and which must have their axes spaced at fixed distances regardless of size. For example, it has great importance in connection with the filling of milk bottles due to the fact that the diameters of different sizes of milk bottles vary to a very marked extent.

The terminology used in the specification is for the purpose of description, and not of limitation, the scope of the invention being indicated in the claims.

I claim:

1. In combination, a conveyer on which articles may be carried at random, a second and orbitally moving conveyer to receive articles from the first conveyer and including holding means to maintain articles in spaced relation, said holding means being changeable to handle articles of different sizes without changing the spacing of the

article axes, and means whereby articles will move from the first conveyer to the second conveyer in synchronism with the holding means comprising a variable speed drive to vary the linear speed of one of the conveyers with respect to the other conveyer.

2. In combination, a straight line conveyer adapted to carry articles at random, a pocketed rotary conveying element changeable to receive articles of various sizes without varying the spacing of the article axes, and means to drive the conveyer and rotary element at relatively variable speeds.

3. In a container filling machine, an infeed conveyer adapted to conduct containers at random, a dial driving means arranged to receive dials of different diameters but each having its pockets similarly spaced circumferentially thereof, guiding elements associated with said dial driving means and adjustable to conform to dials of different diameters, and means to drive said conveyer and dial driving means at relatively variable speeds.

4. In combination, a conveyer, a rotary conveying means arranged to receive articles from the conveyer, the rotary conveying means being changeable to handle runs of articles of different diameters without varying the spacing of the article axes, and means to drive the conveyer and rotary conveyer means at relatively variable speeds.

5. In combination, a straight line conveyer adapted to carry articles at random, a pocketed rotary conveying element changeable to receive articles of various sizes without varying the spacing of the article axes or the pitch circle about which the articles move, and means to drive the conveyer and rotary element at relatively variable speeds.

40

ROBERT J. STEWART.
